SELF-PROPELLED TAMPING ROLLER

Carl F. Greiner and John F. Harrison, Springfield, Ohio, assignors to The Buffalo-Springfield Roller Co., Springfield, Ohio, a corporation of Ohio

Application June 4, 1945, Serial No. 597,393

23 Claims. (Cl. 94—50)

1

This invention is a novel improvement in self-propelling tamping rollers, and the principal object thereof is to provide a tamping roller having a traction unit and a trailing unit, each unit carrying parallel tamping rolls provided with sheep's-foot elements, each said roll being mounted for independent tilting movement on a horizontal axis disposed parallel with the longitudinal axis of the tamping roller, the units being pivotally connected together in such a manner as to provide a minimum wheel base for the tamping roller, and to provide a minimum turning radius rendering it possible to turn the tamping roller around for the return trip instead of having to reverse the drive as in conventional tamping rollers, the convenience achieved by turning the machine around after travel in the one direction being of considerable value since such arrangement renders it possible to use in the tamping roller a conventional truck or tractor type transmission with complete satisfaction, owing to the fact that the turning around of the tamping roller will cause the roller to travel in the forward gear at all times; however, a reversible transmission may be used in place of the conventional truck or tractor type transmission with complete satisfaction.

Our present invention is an improvement upon the tamping roller shown in U. S. Letters Patent No. 2,226,182 issued December 24, 1940 to Matthew S. Ross in which the tamping roller is provided with an articulated frame; and the present invention is also an improvement upon the tamping roller shown in our co-pending application, Serial No. 555,098, filed September 21, 1944, (now U. S. Letters Patent No. 2,437,524, dated March 9, 1948).

Other minor objects of the invention will be hereinafter set forth.

We will explain the invention with reference to the accompanying drawings which show several practical embodiments thereof, to enable others familiar with the art to adopt and use the same; and will summarize in the claims the novel features of construction, and novel combination of parts, for which protection is desired.

In said drawings:

Figure 1 is a side elevation of one form of tamping roller embodying our invention.

Fig. 2 is a top plan view, partly in section, of the tamping roller shown in Fig. 1.

Fig. 3 is a horizontal section on the line 3—3, Fig. 1, through one of the drive rolls of the traction unit of the tamping roller shown in Fig. 1,

showing the driving connections for the roll, and the pivots of the sub frame carrying the drive roll.

Fig. 4 is an enlarged vertical section through the pivotal connection of the traction and trailing units of the tamping roller shown in Fig. 1.

Fig. 5 is a side elevation of a modified form of tamping roller, embodying our invention.

Fig. 6 is a top plan view partly in section of the tamping roller shown in Fig. 5.

Fig. 7 is an enlarged vertical section through the pivotal connection between the traction and trailing units of the tamping roller shown in Fig. 5.

Fig. 8 is a side elevation of a further modified form of tamping roller, embodying our invention.

Fig. 9 is a top plan view partly in section of the tamping roller shown in Fig. 8.

Fig. 9a is an enlarged detail section through the pivots of the center subframe of the trailing unit.

Fig. 10 is a side elevation of the traction unit shown in Fig. 1 equipped with a gear drive instead of a chain drive.

Fig. 11 is a horizontal section on the line 11—11, Fig. 10.

As shown in Figs. 1—4, the tamping roller comprises a traction unit A carrying the drive rolls, the motor and transmission, also the operator's cab housing the necessary controls, and a trailing unit B carrying the trailing rolls, said units A and B being connected together by a pivotal connection C whereby the units A and B may be articulated for steering purposes, the pivotal connection permitting the turning of the trailing unit B with respect to the traction unit A on both horizontal and vertical axes.

The traction unit A comprises a chassis in which is mounted a motor 1, driving through speed-change gearing contained in casing 2 a differential housed in casing 3, said differential being of T-type, and units 1, 2 and 3 being disposed in alignment, with the differential disposed adjacent the rear end of the traction chassis.

The motor 1 and parts 2 and 3 may be covered by a hood 4 terminating at the rear in a cab 5 in a manner similar to an ordinary truck, said cab 5 housing the driver's seat 6 and the necessary motor and steering controls (not shown).

Extending from each side of the traction chassis are spaced parallel arms 7—8, the rear arms 8 being disposed in advance of the T-shafts 3a of differential 3. In each pair of arms 7—8 is journaled a rectangular sub frame 9 pivoted as at 9a on its center line on a horizontal axis

parallel with the longitudinal axis of the chassis, whereby each sub frame 9 is permitted to swing freely on its axes 9a. Mounted on an axle 10 journaled in each sub frame 9 is drive roll carrying tamping elements 12 preferably of the sheep's-foot or any other desired type, arranged in any desired manner and extending radially of the roll 11.

By the above construction the rolls 11, which are the drive rolls journaled in pivoted sub frames 9, are thus permitted to pivot independently on horizontal axes 9a, so that in traversing the earth or ground each individual roll 11 may adjust itself to suit the contour of the underlying ground.

The means for driving the drive rolls 11 from differential 3 is preferably but not necessarily substantially the same as disclosed in our co-pending application Serial No. 555,098, (Patent 2,437,524), above mentioned, the drive being shown more particularly in Fig. 3. The drive rolls 11 including integral hubs 11a are freely rotatably mounted upon the axles 10, the outer ends of the hubs providing suitable means to prevent axial movement of said rolls 11 on axles 10. On the outer end of each drive roll 11 is a drive sprocket 13. On each sub frame 9 opposite the sprocket 13 is a bracket 14 adapted to swing with the sub frame, said bracket being bifurcated and a shaft 15 is rotatably journaled in the bifurcations, as shown in Fig. 3, shaft 15 carrying a sprocket 16 opposite its related sprocket 13; and a chain 17 runs around each pair of sprockets 13 and 16.

The inner end of shaft 15 carries a universal joint 18; and the outer end of the adjacent differential shaft 3a carries a universal joint 19 (Fig. 3) a shaft section 20 connecting the opposed members of the universal joints 18-19, shaft 23 being preferably splined thereto as shown in Fig. 3 so as to permit elongation or contraction of the shaft assembly 3a, 19, 20, 18, 15 as the related subframe 9 pivots on its axes 9a. By mounting the sprocket 16 on the subframe 9 it is obvious that, as the sub-frame pivots, the relation between the sprockets 13 and 16 remains constant, and the sprockets remain at all times in the same plane; and hence swinging of the sub-frames 9 does not in any way affect the driving connections of the drive rolls 11 since the splined connections between shafts 20 and the universal joints 18, 19 allows for lengthening and shortening of the drive for the rolls 11.

The trailing unit B comprises a rectangular frame 21 with laterally projecting pairs of arms 22, 23 at each side, in which are pivotally mounted subframes 24 of substantially similar size and shape as the sub-frames 9, said sub-frames being pivoted on horizontal pivots 24a at each end in the arms 22, 23. In each sub-frame 24 is mounted a tamping roll 25 freely rotatably mounted upon an axle 26, each roll 25 being provided with tamping elements 27 similar to the tamping elements 12 of the drive rolls 11. Preferably the rolls 25 are of the same diameter and width as the drive rolls 11. Pivots 24a are preferably disposed the same distance from the longitudinal axis of the tamping roller as the pivots 9a of the sub-frames 9 of the traction unit A, so that the tamping rolls 25 carried by the sub-frames 24 of trailing unit B will substantially follow the drive rolls 11 of the traction unit A. By the above construction the tamping rolls 25 for trailing unit B are permitted to swing individual-

ly on horizontal axes in their sub-frames 24 so as to follow the contour of the underlying ground.

The pivotal connection C between the tractor unit A and trailing unit B is shown more particularly in Fig. 4, the same comprising a vertically disposed king pin 28 rigidly mounted centrally upon the rear end of the chassis of the traction unit A, as shown, preferably by means of a bracket 29, said king pin 28 having a cap plate 30 removably secured to its upper end by means of bolts 31 (Figure 4).

Pivoted upon king pin 28 is the hub 32 of a horizontal drawbar 33, which hub is confined on the king pin between the bracket 29 and the cap plate 30. Drawbar 33 carries a fixed bolt 34 (Fig. 4) disposed axially thereof extending from its rear end on which bolt 34 is pivotally mounted for rotation on a horizontal axis a drawbar terminal 35 maintained on bolt 34 by a nut 36, a bushing 37 being preferably disposed around the bolt 34. Thus the terminal member 35 is permitted to swivel on a horizontal axis on bolt 34. The rear end of terminal member 35 is rigidly secured in any desired manner to the center of the front end of the trailing unit B. By the above construction, the trailing unit B is permitted to swivel as a unit on both vertical and horizontal axes with respect to the traction unit A.

30 In order to effect steering of the tamping roller, hydraulic means are preferably provided, the same consisting of a depending bracket 38 on the drawbar 33 to which is pivoted, as at 39a, one end of a double-acting hydraulic cylinder 39 disposed substantially horizontally between the units A and B, said hydraulic cylinder housing a piston carrying a rod 40 the outer end of which is pivotally connected as at 41 to a bracket 42 (Fig. 2) secured to the rear end of the chassis of the traction unit A adjacent one outer side thereof. Cylinder 39 is provided with inlet and outlet pipes (not shown) connected in a pressure fluid circuit whereby fluid may be admitted into either end of cylinder 39 to shift the piston and its rod 40 to swing the units A and B on the king pin 28 thus effecting steering. The use of hydraulic steering cylinders such as 39, and their fluid circuits, is well known in the roller art; and, therefore, needs no detailed description herein.

50 The arrangement of units A and B and pivotal connections C provides a tamping roller having a much shorter wheel base than those heretofore constructed, with the result that the tamping roller will have a much shorter turning radius, thus making it practicable and possible to turn the tamping roller around for the return trip instead of having to reverse the drive as in the conventional tamping rollers. Tamping rollers usually travel farther in the rolling cycle than 60 do conventional three-wheel road-rollers, and thus the general convenience achieved by our invention in turning the machine around in a short radius is of considerable value, although it may be desired to retain the conventional reversible transmission disclosed in our co-pending application Serial No. 555,098 (Patent 2,437,524) before mentioned. Our arrangement thus renders it possible to utilize the usual truck or tractor type transmission with complete satisfaction, due 65 to better opportunity to turn the machine around and travel in a forward direction of gear at all times. Furthermore, in our novel tamping roller the driving rolls 11 precede and pull the trailing rolls 25, and hence the latter offer less rolling resistance than if same were pushed. Moreover,

since the rolls 25 that are not driven are arranged as trailing rolls, a greater number of such rolls 25 may be utilized in the assembly, thus increasing the efficiency of the tamping roller.

By the above construction the traction unit A is articulated for steering with respect to the trailing and supporting unit B. Thus the driving rolls 11 are also the steering rolls; however, each of the rolls 11 and 25 are mounted to oscillate freely in their sub-frames 9 and 24 at all times to follow the ground contour. The use of the horizontal pivot bolt 34 on which the drawbar terminal 35 is pivoted not only allows oscillation of the trailing unit B with respect to the traction unit A, but also relieves frame strains as well as permits the rolls to better follow the contour of the ground.

In Figs. 1-4 inclusive, the vertical king pin 28 is disposed in rear of the axis of axles 10 of drive rolls 11 of the traction unit A. But in Figs. 5, 6, 7 a modification is shown in which a traction unit A', trailing unit B' and the pivotal connection C' are utilized, the same being generally similar to those described in connection with the preceding Figures 1-4. However, in this modification the motor 1 is placed over the transmission 2 and over the differential 3, and in this arrangement the differential 3 and transmission 2 are disposed forwardly of the arrangement shown in the preceding figures to permit the location of the vertical king pin directly over and in line with the axis of the axles 10 of the drive rolls 11, thus providing correct steering from a geometrical standpoint when the machine is not traveling, such arrangement being particularly desirable when loading the roller on freight cars, or turning in tight places while at a standstill. In this arrangement the drive shafts 3a project from the differential housing 3 in front of the drive rolls 11 instead of in rear thereof as in the preceding figures. The arrangement of shaft and sprocket drive from the differential shaft sections 3a to drive the drive rolls 11, however, is otherwise the same as described in connection with the preceding figures, and similar parts are similarly lettered and hence the drive needs no detailed description herein, except to state that the brackets 14 for supporting the shafts 15 of the drive sprocket 16 are disposed at the front outer ends rather than at the rear outer ends of the sub frames 9, as in the preceding figures, the drive rolls 11 being mounted in sub frames 9 pivoted on horizontal axes as in the preceding figures.

In this modification the trailing unit B' is also substantially identical with the trailing unit shown in the preceding figures, and hence needs no specific description herein. In this modification the cab 5 shown in the preceding figures is omitted; however, it is obvious that a cab may be provided above the operator's seat 6, if desired.

As above stated, the pivotal connection C' between the units A' and B' is disposed above and in line with the axis of the axles 10 of the drive rolls 11 as shown in Fig. 6, the pivotal connection being shown more particularly in Fig. 7. The king pin 28 carries a cap plate 30 secured by screws or bolts 31 as in the preceding figures, the hub 32 of the drawbar being confined between the bracket 29 and cap plate 30. Hub 32 carries a horizontal bolt 34 for the drawbar terminal 35 secured by a rigid frame 43 to the front end of the trailing unit B', which unit is thereby permitted to pivot with respect to the traction unit A' on the horizontal axis (bolt 34) and vertical axis (king pin 28) as in the preceding figures.

In this modification the hub 32 of the drawbar

has rigidly secured thereto a bracket plate 44 (Figures 6, 7) normally projecting rearwardly and laterally with respect to the longitudinal axis of the tamping roller, as shown in Fig. 6. The outer end of the piston rod 40 is pivotally connected as at 40a to the bracket 44, while the opposite end of the double acting cylinder 39 is pivotally connected as at 39a to a bracket 45 (Fig. 7) carried by the chassis of traction unit A' at the opposite side of the longitudinal axis of the frame A from the pivot 40a, as clearly shown in Fig. 6. Thus by admission of fluid under pressure to either end of cylinder 39 the piston rod 40 will be actuated to pivot the trailing unit B' with respect to the traction unit A'.

The operation of the tamping roller shown in Figures 5, 6, 7 is identical with that shown in the preceding figures, but the arrangement of the king pin 28 above the axis of the axles 10 of the driving rolls 11 permits easy steering when the machine is not traveling, which is a desirable feature.

In Figures 8, 9, a further modification of the tamping roller is shown in which the traction unit A2 and the pivotal connection C2 between the traction unit A2 and the trailing unit B2 is substantially identical with that shown in Figures 5, 6, 7. However, in this modification the frame of the trailing unit B2 consists of cross members 50, 51 which are connected at their outer ends by parallel arched frame members 52. Trailing unit B2 carries three individually pivoted tamping rolls, the outer tamping rolls 53 being journaled in sub-frames 54 in a manner similar to the sub-frames 24 shown in Figure 6, the sub-frames being pivoted on horizontal pivots 54a at the outer ends of the cross members 50, 51 preferably under the arched frame members 52. At the forward end of the frame of trailing unit B2 is a cross member 55 (Fig. 9) provided with horizontal pivots for the sub-frame 57 of the center roll 58. As shown in Fig. 9a the horizontal pivots for sub-frame 57 which carries center roll sub-frame 59 for center roll 58 consists of spaced perforated lugs 56a on cross member 55 between which perforated lugs 56 on sub-frame 57 enter, pivot pins 56b passing through the registering perforations in the lugs 56-56a. In this manner the center roll 58 can rise or lower vertically to better follow the contour of the ground, the center roll inner sub-frame 59 being journaled for oscillation in sub-frame 57 at pivots 60 in a manner similar to the sub-frames 54 in their pivots 54a.

The trailing unit B2 carries a rear extension 61 which includes a ball socket 63, and ball head 62 connects drawbar 64 to a trailing sub-frame 65 of the trailing roll 66; the ball and socket connection permitting independent universal oscillation of the sub-frame 65 carrying roll 66 and hence a pivot in the sub-frame 65 is not necessary in view of the ball and socket connection. Roll 66 is journaled in its sub-frame 65 in a manner similar to the other rolls.

In this modification it will be noted that the addition of center roll 58 of the trailing unit B2 and the final trailing roll 66 constitute the chief difference over the arrangement shown in Figures 5, 6 and 7. The machine shown in Figures 8, 9 would therefore tamp the full width of the machine, and two rolls would pass over the entire area being tamped upon each passage of the machine. In Figs. 1-7 there is considerable space between the drive rolls of the traction units A or A' and between the rolls of the trailing units B or B'. The type shown in Figs. 8, 9 better

lends itself to designs of large heavy tamping rollers.

Figs. 10 and 11 show a modification of the drive for the drive rolls 11 of the traction unit, gear trains being utilized instead of the chain and sprocket drives disclosed in the preceding figures. For purposes of illustration the gear train arrangement is shown in connection with the tamping roller construction shown in Figs. 1 to 3 inclusive. However, it is understood that the gear train drive may be obviously utilized in connection with any of the remaining prior modifications in lieu of the chain and sprocket drive.

In Figs. 10 and 11 the main parts are similar to corresponding parts shown in Figs. 1 and 3, and similar parts are similarly numbered. In this modification, however, the drive roll 11 carries a gear 80, in place of the chain sprocket 13 of Fig. 3, and the stub shaft 15 carries a pinion 81 disposed in alignment with gear 80. An idler gear 82 is journaled on a stub shaft 83 mounted in the adjacent side of the sub frame 9, said gear 82 meshing with both gears 80 and 81 respectively, as clearly shown in Figs. 10 and 11. However, two or more idler gears may be utilized in place of the single gear 82, if desired.

Since the shaft 15 is journaled in bracket 14 carried by the sub frame 9 the same will remain at all times parallel with the axle 10 of the drive roll 11 for any tilting or swinging positions of the sub frame, and hence the gear train 80, 81 and 82 will constantly remain in proper meshing relation during swinging of the sub frame 9. Thus the gear train drive shown in Figs. 10 and 11 may obviously be applied to the modifications shown in Figs. 1 to 4 inclusive, Figs. 5 to 7 inclusive, and Figs. 8 and 9 inclusive.

The platform or frames of the trailing units B and B' are well adapted to carry extra ballast, where desired. The roll diameters are unlimited by other elements of the machine such as the front roll mounting shown in our copending application Serial No. 555,098.

In each modification of machine shown by placing the driving rolls at the front end of the tamping roller, a greater number of rolls can be utilized, because the rolls which are not driven will be pulled at all times and will therefore offer less rolling resistance than if they were pushed.

We do not limit our invention to the exact forms shown in the drawings, for obviously changes may be made therein within the scope of the claims.

We claim:

1. A self-propelled roller, comprising a traction unit; a pair of parallel drive rolls mounted in sub-frames carried by said unit on horizontal pivots for oscillation on horizontal axes parallel with the longitudinal axis of the traction unit; a motor in said unit actuating a differential having laterally disposed shaft sections; devices actuated by the shaft sections for driving the said drive rolls; a combined trailing and supporting unit; a roll mounted in a sub-frame carried by said trailing unit on horizontal pivots for oscillation on a horizontal axis parallel with the longitudinal axis of the trailing unit; coupling means including a vertical pivot and a horizontal pivot, said means connecting the said units together on an axis extending between said drive rolls, said connecting means permitting swinging of the units about a vertical axis between the drive rolls and permitting relative swivelling of the units about a horizontal axis; and means for swinging

the units about said vertical axis to effect steering.

2. In a roller as set forth in claim 1, said devices comprising transversely disposed stub shafts journaled in brackets carried by the sub-frames of the traction unit opposite the differential shaft sections; aligned sprockets carried by the drive rolls and stub shafts respectively; and chains running around the aligned sprockets for driving the respective drive rolls.

3. In a roller as set forth in claim 1, said devices comprising transversely disposed stub shafts journaled in brackets carried by the sub-frames of the traction unit opposite the differential shaft sections; aligned gears carried by the drive rolls and stub shafts respectively; and idler gears journaled in the sub frames meshing with said aligned gears.

4. In a roller as set forth in claim 1, said coupling means comprising a vertical king pin carried by the traction unit in the vertical plane of the steering axles; a horizontal drawbar having a hub journaled on said king pin; and a head swiveled on said drawbar and rigidly connected with the trailing unit on the axis thereof.

5. In a roller as set forth in claim 1, said coupling means comprising a vertical king pin carried by the traction unit in the vertical plane of the steering axles; a horizontal drawbar having a hub journaled on said king pin; and a head swiveled on said drawbar and rigidly connected with the trailing unit on the axis thereof; and said swinging means comprising a double-acting hydraulic cylinder having a piston rod and disposed at an angle to the longitudinal axis of the roller, said piston rod and opposite end of the cylinder pivotally connecting the drawbar and traction unit.

6. A self-propelled tamping roller, comprising 40 a traction unit; a pair of parallel drive rolls carrying tamping elements and mounted in sub frames carried by said unit on horizontal pivots for oscillation on horizontal axes parallel with the longitudinal axis of the traction unit; a motor 45 in said unit actuating a differential having laterally disposed shaft sections to serve as a drive means; flexible and elongatable shafting extending from said differential shaft sections to serve as a drive means; driven means actuated by the 50 shafting for driving the said drive rolls while permitting the rolls to oscillate freely; a combined trailing and supporting unit; a roll carrying tamping elements and mounted in a sub frame carried by said trailing unit on horizontal 55 pivots for oscillation on a horizontal axis parallel with the longitudinal axis of the trailing unit; coupling means including a vertical pivot and a horizontal pivot, said means connecting said units together on an axis extending between said drive rolls, said connecting means permitting swinging of the units about a vertical axis between the drive rolls and permitting relative swivelling of the units about a horizontal axis; and means for swinging the units about said vertical axis to effect steering.

7. In a tamping roller as set forth in claim 6, said driven means comprising transversely disposed stub shafts journaled in brackets carried by the sub frames of the traction unit opposite 70 the differential shaft sections; aligned sprockets carried by the drive rolls and stub shafts respectively; chains running around the aligned sprockets for driving the respective drive rolls; and said flexible and elongatable shafting comprising splined sectional shafts connected at their

ends by universal joints to the stub shafts and differential shaft sections respectively.

8. In a tamping roller as set forth in claim 6, said driven means comprising transversely disposed stub shafts journaled in brackets carried by the sub frames of the traction unit opposite the differential shaft sections; aligned gears carried by the drive rolls and stub shafts respectively; idler gears journaled in the sub frames meshing with said aligned gears; and said flexible and elongatable shafting comprising splined sectional shafts connected at their ends by universal joints to the stub shafts and differential shaft sections respectively.

9. In a tamping roller as set forth in claim 6, said coupling means comprising a vertical king pin carried by the traction unit in the vertical plane of the steering axles; a horizontal drawbar having a hub journaled on said king pin; and a head swiveled on said drawbar and rigidly connected with the trailing unit on the axis thereof.

10. In a tamping roller as set forth in claim 6, said coupling means comprising a vertical king pin carried by the traction unit in the vertical plane of the steering axles; a horizontal drawbar having a hub journaled on said king pin; and a head swiveled on said drawbar and rigidly connected with the trailing unit on the axis thereof; and said swinging means comprising a double-acting hydraulic cylinder having a piston rod and disposed at an angle to the longitudinal axis of the roller, said piston rod and opposite end of the cylinder pivotally connecting the drawbar and traction unit.

11. A self-propelled tamping roller, comprising a traction unit; a pair of parallel drive rolls carrying tamping elements and mounted in sub frames carried by said unit on horizontal pivots for oscillation on horizontal axes parallel with the longitudinal axis of the traction unit; a motor in said unit actuating a differential having laterally disposed shaft sections; flexible and elongatable shafting extending from said differential shaft sections; driven means actuated by the shafting for driving the said drive rolls while permitting the rolls to oscillate freely; a combined trailing and supporting unit; a second pair of parallel rolls carrying tamping elements and mounted in sub frames carried by said trailing unit on horizontal pivots for oscillation on horizontal axes parallel with the longitudinal axis of the trailing unit; coupling means including a horizontal pivot and a vertical pivot, said means connecting the traction and trailing units together on an axis extending between said drive rolls, said connecting means permitting swinging of the units about a vertical axis between the drive rolls and permitting relative swiveling of the units about a horizontal axis; and means for swinging the units about said vertical axis to effect steering.

12. In a tamping roller as set forth in claim 11, said driven means comprising transversely disposed stub shafts journaled in brackets carried by the sub frames opposite the differential shaft sections; aligned sprockets carried by the drive rolls and stub shafts respectively; chains running around the aligned sprockets for driving the respective drive rolls; and said flexible and elongatable shafting comprising splined sectional shafts connected at their ends by universal joints to the stub shafts and differential shaft sections respectively.

13. In a tamping roller as set forth in claim

11, said driven means comprising transversely disposed stub shafts journaled in brackets carried by the sub frames of the traction unit opposite the differential shaft sections; aligned gears carried by the drive rolls and stub shafts respectively; idler gears journaled in the sub frames meshing with said aligned gears; and said flexible and elongatable shafting comprising splined sectional shafts connected at their ends by universal joints to the stub shafts and differential shaft sections respectively.

14. In a tamping roller as set forth in claim 11, said rolls of each unit being spaced apart; and the rolls of the trailing unit tracking those of the traction unit.

15. In a tamping roller as set forth in claim 11, said rolls of the traction unit being spaced apart; and the rolls of the trailing unit tracking those of the traction unit; an intermediate tamping roll journaled in an intermediate sub frame disposed between the rolls of the trailing unit; said intermediate sub frame being disposed on the longitudinal axis of the trailing unit and mounted in horizontal pivots for oscillation on a horizontal axis; one end of the intermediate sub frame being connected in the trailing unit to permit same to swing thereon on a horizontal axis transversely of the trailing unit; and a third tamping roll journaled in a third sub frame disposed in rear of the intermediate tamping roll; said third sub frame being connected to the rear end of the trailing unit for universal swinging movement.

16. In a tamping roller as set forth in claim 35 11, said coupling means comprising a vertical king pin carried by the traction unit in the vertical plane of the steering axles; a horizontal drawbar having a hub journaled on said king pin; and a head swiveled on said drawbar and rigidly connected with the trailing unit on the axis thereof.

17. In a tamping roller as set forth in claim 11, said coupling means comprising a vertical king pin carried by the traction unit in the vertical plane of the steering axles; a horizontal drawbar having a hub journaled on said king pin; and a head swiveled on said drawbar and rigidly connected with the trailing unit on the axis thereof; and said swinging means comprising a double-acting hydraulic cylinder having a piston rod and disposed at an angle to the longitudinal axis of the roller, said piston rod and opposite end of the cylinder pivotally connecting the drawbar and traction unit.

18. A self-propelled tamping roller, comprising a traction unit; a pair of parallel drive rolls carrying tamping elements and mounted in sub frames carried by said unit on horizontal pivots for oscillation on horizontal axes parallel with the longitudinal axis of the traction unit; a motor in said unit actuating a differential having laterally disposed shaft sections; said motor and differential being aligned and the shaft sections of the differential being disposed adjacent the rear ends of the sub-frames; flexible and elongatable shafting extending from said differential shaft sections; devices actuated by the shafting for driving the said drive rolls while permitting the rolls to oscillate freely; a combined trailing and supporting unit; a second pair of parallel rolls carrying tamping elements and mounted in sub frames carried by said trailing unit on horizontal pivots for oscillation on horizontal axes parallel with the longitudinal axis of the trailing unit; coupling means including a ver-

tical pivot and a horizontal pivot, said means connecting the traction and trailing units together on an axis extending between said drive rolls, said connecting means permitting swinging of the units about a vertical axis between the drive rolls and permitting relative swiveling of the units about a horizontal axis; vertical pivot of the coupling being disposed in rear of the axles of the drive rolls; and means for swinging the units about said vertical axis to effect steering.

19. In a tampering roller as set forth in claim 18, said rolls of the traction unit being spaced apart; and the rolls of the trailing unit tracking those of the traction unit; an intermediate tamping roll journaled in an intermediate sub frame disposed between the rolls of the trailing units; said intermediate sub frame being disposed on the longitudinal axis of the trailing unit for oscillation on a horizontal axis; one end of the intermediate sub frame being connected in the trailing unit to permit same to swing therein on a horizontal axis transversely of the trailing unit; and a third tamping roll journaled in a third sub-frame disposed in rear of the intermediate tamping roll; said third sub-frame being connected to the rear end of the trailing unit for universal swinging movement.

20. In a tamping roller as set forth in claim 18, said coupling means comprising a vertical king pin carried by the traction unit on the axis thereof; a horizontal drawbar having a hub journaled on said king pin; and a head swiveled on said drawbar and rigidly connected with the trailing unit on the axis thereof; and said swinging means comprising a double-acting hydraulic cylinder having a piston rod and disposed at an angle to the longitudinal axis of the roller, said piston rod and the opposite end of the cylinder pivotally connecting the drawbar and traction unit.

21. A self-propelled tamping roller, comprising a traction unit; a pair of parallel drive rolls carrying tamping elements and mounted in sub frames carried by said unit on horizontal pivots for oscillation on horizontal axes parallel with the longitudinal axis of the traction unit; a motor in said unit actuating a differential having laterally disposed shaft sections; said motor being disposed above the differential with the shaft sections of the differential disposed adjacent the front ends of the sub frames; flexible and elongatable shafting extending from said differential shaft sections; driven means actuated by the shafting for driving the said drive rolls while permitting the rolls to oscillate freely; a combined trailing and supporting unit; a second pair of parallel rolls carrying tamping elements and mounted in sub frames carried by said trail-

ing unit on horizontal pivots for oscillation on horizontal axes parallel with the longitudinal axis of the trailing unit; coupling means including a vertical pivot and a horizontal pivot, said means connecting the traction and trailing units together on an axis extending between said drive rolls, said connecting means permitting swinging of the units about a vertical axis between the drive rolls and permitting relative swiveling of the units about a horizontal axis; said vertical pivot of the coupling unit being disposed directly above the axles of the drive rolls; and means for swinging the units about said vertical axis to effect steering.

22. In a tamping roller as set forth in claim 21, said rolls of the traction unit being spaced apart; and the rolls of the trailing unit tracking those of the traction unit; an intermediate tamping roll journaled in an intermediate sub frame disposed between the rolls of the trailing units; said intermediate sub frame being disposed on the longitudinal axis of the trailing unit for oscillation on a horizontal axis; one end of the intermediate sub frame being connected in the trailing unit to permit same to swing therein on a horizontal axis transversely of the trailing unit; and a third tamping roll journaled in a third sub frame disposed in rear of the intermediate tamping roll; said third sub frame being connected to the rear end of the trailing unit for universal swinging movement.

23. In a tamping roller as set forth in claim 21, said coupling means comprising a vertical king pin carried by the traction unit on the axis thereof; a horizontal drawbar having a hub journaled on said king pin; and a head swiveled on said drawbar and rigidly connected with the trailing unit on the axis thereof; and said swinging means comprising a double-acting hydraulic cylinder having a piston rod and disposed at an angle to the longitudinal axis of the roller, said piston rod and the opposite end of the cylinder pivotally connecting the drawbar and traction unit.
